GAS LIGHTER CONSTRUCTION

Earl W. Roberts, Detroit, Mich., assignor to Roberts Brass Manufacturing Company, Detroit, Mich., a Corporation of Michigan

Application August 17, 1931. Serial No. 557,675

7 Claims. (Cl. 158—115)

This invention relates generally to gas lighter constructions and refers more particularly to those of the push button valve type described for use in connection with the gas burners of stoves 5 and ranges having concealed manifolds.

One of the essential objects of the invention is to provide a lighter of the type mentioned wherein in the body of the valve is formed of two sections which may be assembled after one of said sections 10 is secured to the concealed manifold.

Another object is to provide a connection between the sections referred to that will enable the push button of the valve while assembled with the second section to be inserted through 15 the front wall of the stove, and the second section to be subsequently connected to the first section.

Another object is to provide a construction which will enable the connection aforesaid to be made easily and quickly after the manifold has 20 been secured in place without dismantling either the lighter or stove and without any of the lighter parts striking or swinging against any of the parts of the stove.

A further object is to provide a lighter that is 25 simple and neat in design, that can be manufactured at a comparatively low cost, that is sturdy and compact in construction and that is safe and reliable.

Other objects, advantages and novel details of 30 construction of this invention will be made more apparent as this description proceeds, especially when considered in connection with the accompanying drawings, wherein:

Figure 1 is a perspective view of a stove with 35 a lighter embodying my invention applied thereto;

Figure 2 is a vertical sectional perspective view through the front wall of the stove;

Figure 3 is a plan view of the lighter valve unit; 40 Figures 4, 5 and 6 are vertical sectional views taken on the lines 4—4, 5—5 and 6—6 of Figure 3;

Figure 7 is a detail perspective view of the lower section of the valve body.

Referring now to the drawings, A is a gas stove 45 of conventional design having a burner compartment 1 provided with a front wall 2 and a top grating 3. 4 are burners within the compartment; 5 is a gas manifold concealed in the compartment in rear of the front wall 2, and 6 are 50 mixing tubes extending from the manifold 5 to the burners 4.

B is a lighter embodying my invention and 55 preferably comprising a valve unit 6, a firing head 7 and a connecting tube or pipe 8. As shown, the valve unit comprises a sectional body 9, a

valve 10, a push button 11, an adjusting screw 12 and closures 13 and 14 respectively. Preferably the body 9 has two sections 15 and 16 having frusto-conical portions 17 and 18 respectively fitting snugly one within the other and having 60 flat attaching flanges 19 and 20 respectively secured together by screws 21. The lower section 15 has an externally threaded nipple 22 projecting from its lower face at approximately the center thereof for engagement with the gas manifold 5, 65 while the upper section 16 has an interiorly threaded socket 23 in one side thereof for receiving one end of the pipe 8. Suitable connecting passages 24, 25, 26, 27, 28 and 29 respectively and sockets 30 and 31 respectively are provided in 70 the upper section 16 to conduct gas from the nipple 22 to the socket 30. As shown, the passage 24 is in vertical alignment with the passage 32 in the nipple 22 when the sections 15 and 16 are together and extends above the socket 31 to a 75 point just below the socket 30. The passage 25 connects the socket 31 with the passage 26 and the passage 27 connects the passage 26 with the socket 30. The passage 26 extends above the passage 27 and receives the closure 13, while the 80 socket 31 is preferably in line with the passage 25 so as to permit insertion or removal of the valve 10 and receives the plug 14. The passages 28 and 29 are restricted and cooperate with the socket 40 to form a by-pass between the passage 85 24 and socket 30 respectively.

The valve 10 has a substantially frusto-conical portion 41 that normally seats against a similar portion 42 of the section 16 at the inner end of the socket 31 and has a stem 43 projecting through the rear wall 44 of the passage 25 into a laterally opening socket 45 at one side of the section 16 and connected to the push button 11. Suitable packing 46 surrounds the stem 43 within the socket 45 and is held firmly in place by a coil spring 48 sleeved on the stem between the packing and push button. 90

The adjusting screw 12 threadedly engages the walls of the socket 40 and has a pointed end 50 for controlling the flow of gas through the passage 28 from the passage 24. 95

Thus with the construction as described, the lower section 15 alone may be readily secured to the manifold 5, and the upper section 16 with the valve 10, push button 11 and associated parts all assembled may be easily and quickly secured to or detached from the lower section 15 without interference with the front wall 2 by merely manipulating the screws 21 as desired. 105

After the parts are installed adjustment of the 110

screw 12 will permit the proper flow of gas from the manifold 5 to the pipe 8, and unseating of the valve 10 by inward manipulation of the push button 11 will permit gas to flow past the seat 5 42 to the pipe 8.

While it is believed that from the foregoing description the nature and advantages of the invention will be readily apparent, I desire to have it understood that I do not limit myself to what 10 is herein shown and described and that such changes may be resorted to when desired as fall within the scope of what is claimed.

What I claim as my invention is:

1. The combination with a gas stove having an 15 upright wall, a gas manifold in rear of said wall, and a gas burner in rear of and connected to said manifold, of a gas lighter for said burner including a firing head adjacent the burner, a sectional valve unit in rear of said wall, one section of said 20 unit having a nipple portion connected to and adapted to receive gas from the manifold, the second section of said valve unit being connected to and adapted to receive gas from the first mentioned section, a gas supply tube for the firing head projecting from one end of the second section, a valve element in said second section for controlling the passage of gas from the first section to said tube, and actuating means for said 25 valve element including an operating member projecting from the other end of the second section through and accessible in front of an opening in the upright wall aforesaid.

2. The combination with a gas stove having an upright wall, and a gas manifold in rear of 30 said wall, of a gas lighter for said burner including two castings secured together and having communicating gas passages, one of said castings having a nipple connected to and adapted to receive gas from said manifold, a gas supply tube 35 for a firing head connected to the second casting and adapted to receive gas from the passage therein, a valve in the second casting for controlling the flow of gas to the tube, and actuating means for the valve including a member projecting 40 from the second casting through an opening in the upright wall aforesaid so as to be accessible from in front of said wall.

3. A gas lighter structure of the self-contained portable unit type including a valve unit comprising two castings detachably secured together and having communicating gas passages, one of said castings having a nipple attachable to a gas manifold of a stove, a gas supply tube for a firing head connected to the second casting and adapted to receive gas from the passage therein, a valve in the second casting for controlling the flow of gas to the tube, and actuating means for 50

the valve including a member projecting laterally from the second casting so as to be insertable through and accessible in front of a wall of the stove.

4. A gas lighter structure of the self-contained portable unit type including a valve unit having 80 separable sections with communicating gas passages, one of said sections having a nipple portion attachable to and adapted to receive gas from a gas manifold, a gas supply tube for a lighter firing head projecting laterally from the second section and adapted to receive gas from the passage therein, a valve for controlling the flow of gas from the nipple to the tube, and actuating means for the valve including an operating member projecting laterally from the second section. 90

5. A gas lighter including a sectional valve unit, a firing head, a tube terminally connected to the firing head and to one section of the valve unit, a valve in the section just mentioned for controlling the passage of gas to the firing head, actuating means for the valve including a push button projecting from said section for insertion through an opening in a wall of a stove, the other section of said unit having a nipple portion attachable to a 100 concealed manifold of the stove and having means for supporting and for conducting gas from the nipple to the section aforesaid. 95

6. A gas lighter including a valve unit having upper and lower sections detachably secured together, the lower section having a nipple portion attachable to a manifold of a stove and having a seat for the upper section, and the upper section having a passage therein adapted to receive gas from the lower section, a firing head, a gas supply tube for the firing head projecting laterally from the upper section and adapted to receive gas from said passage, a valve in the upper section controlling the flow of gas through said passage to said tube, and actuating means for the valve including a push button projecting laterally from the upper section and insertable through an opening in a wall of the stove. 105

7. A gas lighter structure including a valve unit having upper and lower sections, the lower section having a nipple portion attachable to and adapted to receive gas from a gas manifold of a stove, the upper section being connected to and adapted to receive gas from the lower section, a gas supply tube for a lighter firing head projecting laterally from and adapted to receive gas from the upper section, a valve for controlling the passage of gas from the nipple to said tube, and actuating means for the valve including a push button projecting laterally from the upper section. 110 115 120 125 130
